(57) **CLAIM**

The ornamental design for a saddle pad, as shown and described.

DESCRIPTION

FIG. 1 is a perspective view of a saddle pad shown in use, showing my new design;

FIG. 2 is left side view of the saddle pad of FIG. 1, shown in a flattened state;

FIG. 3 is a right side view thereof;

FIG. 4 is a rear view thereof;

FIG. 5 is a front view thereof;

FIG. 6 is a top view thereof; and,

FIG. 7 is a bottom view thereof.

The dashed lines on the saddle pad indicate stitching lines and form a part of the claimed design. The broken line showing of a horse in FIG. 1 depicts environmental subject matter, and forms no part of the claimed design. The stippling in the figures depicts areas of the saddle pad with contrasting appearance.
